LIQUID FUEL BURNER

Charles Beetschen, Les Plantaz, Nyon,
SwitzerlandApplication January 16, 1937, Serial No. 120,901
In Switzerland January 20, 1936

3 Claims. (Cl. 158—91)

This invention relates to a burner for the liquid fuels such as mazut, heavy oils, oils from draining the gear cases of internal combustion engines, and the like.

5 An object of the invention is to provide a burner which is not equipped with any fuel spraying means, in order to avoid obstruction of the small passages by impurities contained in the fuel.

10 Another object of the invention is to provide a burner of the kind referred to operating without using compressed air for effecting combustion.

According to the present invention, the burner comprises an air admission conduit, a pipe for 15 supplying fuel by gravity, the outlet of which is located close to the outlet opening of the air admission conduit, a baffle plate adjustably disposed between said opening and the end of the pipe, the fuel being ignited on issuing from the 20 pipe.

The accompanying drawings show, by way of example, two preferred forms of the burner according to the invention.

Fig. 1 shows a vertical sectional view of one 25 form for use in connection with a small sized stove for heating a room for example.

Fig. 2 is a vertical section, according to the median plan of the second preferred form of burner to be used with a boiler furnace.

30 Fig. 3 is an outside front view of this second embodiment.

In the drawings, the same reference numerals designate like parts.

The stove shown diagrammatically in Fig. 1 35 consists of a stove body 1, provided with an exhaust chimney 2. The stove may be of the kind commonly used for heating a room and operated either by coal or wood, but in the use of the burner according to the invention, the discharge door and the ash pit are kept closed to prevent 40 the air as far as possible from entering through said openings.

The burner shown in Fig. 1 comprises a substantially cylindrical, and vertical air admission 45 conduit 3 substantially cylindrical in shape, vertical and it being preferably located centrally in the top portion of the furnace 1. This conduit is provided with a flange 4, extending at a right angle of the conduit body 3, and replacing the ordinary furnace closure, or cover.

50 A vertical pipe 5 constitutes the means for supplying the liquid fuel. This pipe carries a funnel 6 at its upper end, into which the fuel is supplied by means of a device (not shown) for causing the fuel to drip, the amount of flow being ad-

justable. The pipe 5 is arranged axially within the conduit 3 and is maintained in place by screw means 7, mounted in a collar 8, carried by a support 9 secured to the flange 4; thereby rendering the position of the outlet end of the pipe 5 relative to the outlet of the conduit 3 vertically adjustable. 5

A perforated baffle plate 10, carried by the lower end of the pipe 5 is disposed between said end and the outlet opening of the conduit 3. 10 A circular solid plate 11, smaller in diameter than the baffle plate 10 and carried by the latter, is disposed slightly beneath the outlet end of the pipe 5.

A perforated support 12 carrying a cup 13 15 is fixed to the conduit 3 by means of the two arms 14, attached in any convenient manner to a flange 15 enclosing the conduit in an adjustable manner by means of a bolt 16 and its nut 17, thereby also regulating the space between the 20 cup 13 and plate 11.

The operation of the burner shown in Fig. 1 is as follows:

The liquid fuel dripping into the funnel 6 25 flows through the pipe 5 to the lower end of the outlet of the pipe, where said fuel is ignited. To ignite it, use can be made of a pad which is carried by an iron wire, soaked in a liquid fuel, ignited and which is then introduced through the conduit 3 to be discharged onto the baffle 30 plate 10.

The normal draught of the chimney 2 causes 35 fresh air to enter for combustion, through the conduit 3 in the direction of the arrow 18. The fuel therefore ignites on issuing from the pipe 5 and according to the amount of the fuel fed, the combustion will be limited at the outlet end of said pipe, or will extend over the plate 11. In some cases, it could terminate in the cup 13. If due to an excessive supply the fuel should fill 40 up the cup pan and overflow, it would finish burning on the perforated table 12. The flames rise around the conduit 3, but cannot within the conduit owing to the draught of the stove. The baffle plate 10 prevents the admission of air current from blowing out the initially small flame. 45

The adjustment in height of the baffle plate 10 and of the plate 11 as well as the table 12 is effected generally only once according to the 50 nature of the draught of the stove to which the burner is applied.

The burner shown in Fig. 1 can easily be used for all kinds of stoves, boilers, and the like and does not require to be constructed in a great variety of sizes; in fact, the flange 4 can be of 55

a diameter corresponding to the smallest stove and rings can be made to occupy the space existing between said flange and the upper part of the stove.

5 The burner shown in Figs. 2 and 3 is applied to a boiler 1 designating the wall of the boiler furnace. This boiler and its furnace can be of the type commonly used, but the discharge door and the ash pit are kept closed to prevent the air as far as possible from entering through said openings.

The air conduit for this burner comprises a vertical cylinder 3a terminating at its upper end in a slanting cylindrical portion 3b extending 10 in an inclined plane from the body portion 3a. The portion 3b of the air admission pipe carries a plate or flange 4 near its inlet opening thus forming a substantial support for the burner on a heater. Plate 4 engages the wall 1 of the furnace and takes the place of a door for closing the discharge opening 4a of the furnace. The fuel pipe comprises a vertical body portion 5a and a slightly slanting branch portion 5b extending 15 in an inclined plane from the body portion and terminating at its upper free end in a funnel 6 which receives the liquid fuel to be supplied by means of a fuel dripping device (not shown) the rate of flow of which is adjustable. The portion 5a of the pipe 5 passes through the axis of the conduit 3a and is kept in place by means of a nut 7 adjustable on the upper threaded end of the pipe portion 5a. This threaded portion freely extends 20 through a plate 9, closing the upper end of the conduit 3a. It will easily be seen that by turning the nut 7 in either direction, the section 5a can be axially displaced either upward or downward.

At the lower end of the portion 5a is an outlet opening 5c, the position of which can be adjusted 25 in height by means of the nut 7.

40 A perforated baffle plate 10, secured to by the lower end of a vertical rod 20, is adapted to slide freely over the part adjacent the lower end of the pipe section 5a of the pipe 5. This baffle plate is ordinarily disposed between the outlet opening 5c of the fuel and the outlet opening of the conduit. At its upper end the rod 20 slides freely within a bore in the plate 9. In order to operate the rod 20 axially, a bar 22 linked to a crank lever 23 pivoted at 24 to the conduit section 3b, extends 45 through the plate 4 and carries at its outer free end a knob 21. This cranked lever has a slot 25 in which a projection of the rod 20 is engaged. It will easily be seen that by pulling or pushing the knob 21, the cranked lever 23 is made to oscillate either in one direction or in the other, thereby causing an upward or downward movement both of the rod 20 and of the baffle plate 10.

50 The admission end of the conduit, formed by the free end of the portion 3b, has bifurcated 55 part 26 serving to guide the portion of the pipe 5 situated just below the funnel 6, when the nut 7 is operated.

60 The lower end of the portion 5a has attached thereto a cup 13, resting on the bottom of a basin 12, formed by a curved plate, the object of which will be explained hereinafter. Said basin 12, as shown in Fig. 1 is likewise fixed to the portion 5a so as to be displaced therewith on adjusting the nut 7.

65 A supplementary air admission conduit 27 is fixed to the outside wall of the conduit. The conduit 27 is crank-shaped and comprises a vertical portion 27a one end of which opens into the basin 12 and close to the outlet opening of the

70 conduit 3a admitting natural air and of the outlet 5c of the pipe 5 supplying the fuel. This conduit 27 likewise comprises a slanting portion 27b in parallel with the portion 3b; the free end of the portion 27b extends through the plate 4 and opens freely in the open like portion 3b. The lower end of the portion 27a or outlet end of the conduit 27 is flattened to cause the air issuing from said conduit to assume the shape of a fanlike jet sliding along the wall of the basin 10 12, before passing to the outlet opening of the conduit 3 and of the pipe 5.

The plate 4 has an opening which is ordinarily closed by a door 28.

The burner operates as follows: 15
The door 28 is opened to introduce a small quantity of easily inflammable liquid such as petroleum in the cup 13, or a wisp of tow is placed in the basin 12. The liquid or the tow is ignited and the fuel dripping device, supplying the ordinary fuel to the funnel 6 is opened. The fuel dripping into the funnel flows through the pipe 5 to the outlet opening 5c. Here, it is vaporized by the petroleum or by the burning tow and thus the burner is ignited. Once the ignition 25 being effected, a draught is produced through the main air admission conduit 3 and through the supplementary air admission conduit 27, owing to the natural draught of the chimney. The liquid fuel continuing to reach the opening 30 5c is vaporized and burns owing to the air arriving through the admission pipes.

The flames rise around the conduit 3, but cannot ascend inside the conduit owing to the draught of the furnace. The baffle plate 10 prevents the admission current of ordinary air from blowing out the flame, yet small in size. The supplementary air admission 27 causes the air it supplies to act on the flame so as to spread it, so that a complete combustion and a satisfactory 40 operation of the burner are obtained.

Although the burner described with reference to Figs. 2 and 3 is advantageously applied in connection with the heating of boilers (either boilers with central heating or steam engines for 45 example) it is of course to be understood that it may likewise be applied to furnaces of various types.

The burners shown and described are simple in construction and permit of burning liquid fuels. 50 of a great variety which need not necessarily be pure; in fact, these fuels may contain solid bodies without their interfering with the operation of the burner, the latter not having any spraying means with an opening of small size so as to be likely to become obstructed. Contrary, in the burners shown, the outlet of the conduit supplying the fuel is of large size, it providing a sure passage without restriction for the fuel, even if the latter contains impurities in solid state. 55

60 What I claim is:

1. A burner for liquid fuels, comprising a pipe for supplying fuel, an air-admission conduit having its delivery end disposed adjacent to the delivery end of said fuel pipe, the delivery of air 65 through said conduit being effected by natural draft, a baffle disposed between the delivery ends of said conduit and pipe, means operable outside of the burner for adjusting the position of said baffle relatively to said delivery ends thereby to regulate the flame according to the draft, and a supplementary air-admission conduit coextensive with said first conduit and having its delivery end disposed adjacent to the delivery ends of said first conduit and said pipe, said supplementary 70 75 conduit being connected to the air-admission conduit 3a admitting natural air and of the outlet 5c of the pipe 5 supplying the fuel.

conduit being so directed that the air issuing therefrom is delivered in the same direction as that delivered by the first conduit.

2. A burner for liquid fuels, comprising in combination, a fuel-supply pipe and an air-admission conduit disposed in coaxial relation and coextensive throughout the major portion of their length, said fuel-supply pipe having an outlet orifice disposed slightly below the delivery end of said conduit, a liquid fuel combustion basin secured to said pipe below said outlet orifice, means for moving said fuel-supply pipe thereby to vary the distance between its outlet orifice and the delivery end of the conduit without changing the relation between said orifice and the combustion basin, a baffle plate movably encircling said pipe between said basin and the delivery end of the conduit, and means operable outside of the burner for moving said baffle plate to vary its position between the outlet orifice of the fuel pipe and the delivery end of the conduit, the delivery of air through said conduit being effected by natural draft.

20 3. A burner for liquid fuels, comprising in

combination, a fuel-supply pipe and an air-admission conduit disposed in coaxial relation and coextensive throughout the major portion of their length, said fuel-supply pipe having an outlet orifice disposed slightly below the delivery end of said conduit, a liquid fuel combustion basin secured to said pipe below said outlet orifice, means for moving said fuel-supply pipe thereby to vary the distance between its outlet orifice and the delivery end of the conduit without changing the relation between said orifice and the combustion basin, a baffle plate movably encircling said pipe between said basin and the delivery end of the conduit, and means operable outside of the burner for moving said baffle plate to vary its position between the outlet orifice of the fuel pipe and the delivery end of the conduit, the delivery of air through said conduit being effected by natural draft.

CHARLES BEETSCHEN. 20
